FLUSH TOILET ACCESSORY

William Frederick Grant, Hamilton, Ontario,
Canada

Application October 7, 1952, Serial No. 313,576

6 Claims. (Cl. 4—10)

1

This invention relates to plumbing fixtures useable in sanitation systems and, more particularly, to an improved flush toilet.

Perhaps the greatest disadvantage of common flushing toilets, is the excessive noise associated with the flushing function. The inrush of water from the storage tank into the bowl of the toilet creates a great deal of unnecessary and unpleasant noise. To overcome this disadvantage of the usual toilet it is proposed to provide a toilet with silencing attachments, one of which may be installed in the pipe leading from the storage tank to the toilet bowl, and the other of which may be detachably secured over the water orifices leading into the said bowl.

One object of the invention is the provision of a flush toilet which is quiet in its flushing operation.

A further object of the invention is the provision of a silencing attachment useable in flush toilets, which is simple in design, easy to install, easily cleaned, efficient in operation, adaptable to usual flush toilets, and cheap to manufacture.

Yet another object of the invention is the provision of a flush toilet having an aerating device disposed in the pipe leading from the storage tank to the bowl of the said toilet.

Another and more detailed object of the invention is the provision of an attachment which may be installed in flush toilets, and is operable to subdivide the usual streams of water rushing into the toilet bowl into a plurality of finely divided streams of aerated water.

With these and other objects in view which may appear while the description proceeds the invention consists of the novel arrangement of cooperating parts shown in the accompanying drawings forming part of this application and in which—

Figure 1 is a top plan view of one embodiment of the invention showing a silencing member installed in a flush toilet;

Figures 2 is a top plan view of the said silencing member;

Figure 3 is an elevational view illustrative of one way in which the said silencing member may be hinged for installation in the said toilet;

Figure 4 is an enlarged partial elevational view showing the said silencing member in place in the said toilet, and one means by which the said member may be secured;

Figure 5 is a similar view illustrative of the communicative connection between the said silencing member and the main water conduit of the said toilet, and

2

Figure 6 is an elevational view of one form of the said fastening means.

Referring more in detail to the drawings in which similar reference characters designate corresponding parts throughout the several views it will be seen that the invention consists of a common flush toilet 10 having the usual water storage tank 11, and which is fitted with a plurality of silencing members.

10 In Fig. 2, the numeral 12 denotes an elliptical member which may be of any suitable cross section, but, which, in the form shown, is an oval gasket having two terminally hingedly attached portions of flexible elastic materials; e. g.—rubber, plastic or spring steel. The said gasket, preferably, is hinged along its major axis, and is secured to the upper inner edge of the rim of the toilet 10 by a plurality of fastening means, one form of which is hereinafter described in greater detail. The upper surface of the gasket 12 is provided with a plurality of recessed portions or troughs 13 into which is directed, the water for flushing the said toilet. Each said recessed portion or trough is provided with a plurality of screened ducts 14 for aerating the said water on its passage to the bowl of the toilet 10.

The said ducts may be of any cross section and dimensions suited to the intended application, but, preferably, are internally baffled tubular ducts communicatively connecting the troughs 13 to the bowl of the toilet 10. Each duct 14 is provided with an upper terminal flange recessed in the said gasket at the base of the said troughs, and is formed with a plurality of peripheral slots disposed at a region immediately below the gasket 12, through which, air may be drawn into the said duct for aerating the water passing therethrough. A plurality of finely apertured baffles are stacked within the duct and serve to finely divide the said water during passage therethrough.

In order further to silence the sudden rush of water during flushing, the pipe leading from the storage tank 11 to the bowl of the toilet 10 is also provided with an aerating device 15 formed generally as hereinbefore described and in communicative connection with the atmosphere.

One form which the fastening means may take is illustrated in Fig. 6 of the drawing, wherein is shown a terminally threaded bolt 16 of flexible elastic material; e. g.—spring steel, having its upper half split into two outwardly upwardly disposed terminally flanged portions. A washer 55 17 and nut 18 are provided for each said bolt,

In operation, the gasket is folded, placed in the bowl of the toilet 10 and secured in place under the inner top edge of the said bowl by the bolts 16, washers 17 and nuts 18. The said bolts are inserted through the usual water inlets 19 leading into the toilet 10. Water released from the storage tank 11 flows to the main conduit of the said toilet from whence it is received in the troughs 13 of the gasket 12 via the remainder of the orifices 19, and is then discharged through the ducts 14. It is evident that the water will be divided into a multiplicity of inherently quiet aerated streams thus silencing the flushing action.

It is believed that the construction and advantages of the structure shown may be apparent from the foregoing paragraphs taken in conjunction with the accompanying drawings without further detailed description.

While the preferred embodiment of the invention has been disclosed it is understood that minor changes in the construction, combination and arrangement of cooperating parts may be resorted to within the scope of what is claimed without departing from the spirit of the invention.

I claim:

1. A gravity flush toilet comprising, a water storage tank, a toilet bowl, a water conduit connecting the said tank to the said bowl, an aerator in the said conduit, and a detachably secured flexible gasket having a plurality of troughs in communication with the water passages leading into the said bowl and a plurality of water aerating ducts leading from the said troughs through the said gasket.

2. In flushing toilets, a silencing device comprising, a flexible troughed elliptical member in communication with the water inlets to the bowl of the said toilet, a plurality of screened ducts extending through the said member, and means for detachably securing the said member to the said bowl of the toilet.

3. In flushing toilets, a silencing device com-

prising, a flexible elastic elliptical gasket having two or more terminally hingedly attached portions, each said portion being formed with one or more elongated troughs in its upper side, a plurality of screened water-aerating ducts extending vertically downwardly from the said troughs and through the said gasket, and a plurality of fastening means for detachably securing the said gasket in communicative connection with the water inlets to the said bowl.

4. In flushing toilets, a silencing device comprising, a flexible elastic elliptical gasket having two or more terminally hingedly attached portions, each said portion being formed with one or more elongated troughs in its upper side, a plurality of screened water-aerating ducts extending vertically downwardly from the said troughs and through the said gasket, and means for securing the said gasket in communicative connection with the water inlets to the said bowl, the said means being a plurality of nuts, washers and terminally threaded bolts having their upper terminations split into two upwardly diverging terminally flanged portions, the said bolts being formed of elastic material.

5. In combination, a toilet bowl having an annular water channel in its rim with a series of discharge openings, an annular member covering the discharge openings of said water channel, and a series of aerating ducts extending through said member and having communication with the discharge openings of said water channel.

6. In a device of the character described in claim 5 including means for detachably securing said annular member to the rim of said bowl.

WILLIAM FREDERICK GRANT.
